CONVENTION BADGE HOLDER

Gabriel G. Tauber, Victor Building, 724 9th St. NW.,
Washington, D.C.

Filed Dec. 29, 1964, Ser. No. 83,163

Term of patent 14 years

(Cl. D59—8)

I claim:

The ornamental design for a convention badge holder, as shown.
